INVENTOR.

Mark Jefferson,

BY
Arthur B. Jenkins,
ATTORNEY.

UNITED STATES PATENT OFFICE.

MANO JEFFERSON, OF HARTFORD, CONNECTICUT.

ATTACHMENT FOR BATH-TUBS.

1,040,686.

Specification of Letters Patent.

Patented Oct. 8, 1912.

Application filed September 15, 1911. Serial No. 649,496.

To all whom it may concern:

Be it known that I, MANO JEFFERSON, a subject of the Emperor of Austria-Hungary, and a resident of Hartford, in the 5 county of Hartford and State of Connecticut, have invented a new and useful Improvement in Attachments for Bath-Tubs, of which the following is a specification.

My invention relates to the class of devices for producing a shower in a bath tub, and the objects of my invention, among others, is to produce a device of this class, simple in construction and convenient and effective in operation.

15 One form of device embodying my invention and in the use of which the objects above set out as well as others may be attained is illustrated in the accompanying drawings in which:

20 Figure 1 is a perspective view partially in section of a bath tub provided with my improved shower. Fig. 2 is a detail view showing a modified form of adjustable spout. Fig. 3 is a detail view showing a modified 25 form of attachment for the supporting tube or bar. Fig. 4 is a detail view showing the arrangement of the sheaves.

In the accompanying drawings the numeral 5 denotes a bath tub of any ordinary 30 form and construction having the usual roll 6 around the top edge. Clips 7 are formed to hook under the edge of the roll or lip formed thereby, loops 8 being secured to these clips. Supporting straps 9 are secured 35 to the loops and a supporting tube or bar 10 is held by the straps, as shown in Fig. 1 of the drawings.

A sleeve 11 is mounted to slide upon the tube, a neck 12 projecting from the sleeve 40 in position to receive a holder 13 that is slid- 45 able in the neck, the fit of the holder within the neck however being such as to provide sufficient friction to retain the holder in any position to which it may be moved. A socket 14 is located at the end of the holder through which socket a spout 15 extends, this spout being curved at its end and hav- 50 ing a sprinkler 16 secured thereto.

A guide rod 17 is secured at its ends to 55 hangers 18 supported by and depending from the tube or bar 10 and a guide 30 secured to the lower end of the spout is freely slidable on this guide rod.

A flexible tube 19 connects the spout 15 with a faucet or supply 20, the latter being 55 of any suitable form and construction. A

supplemental faucet 21 is located below the faucet 20, this supplemental faucet being included in the connection between the spout 15 and the main faucet 20 and having a foot 60 operated valve 22 located in position to be operated by the foot of the bather.

Sheaves 23 are mounted on the supporting bar 10, cords 24 extending over these sheaves and terminating in handles 25 one end of 65 each cord being secured to the sleeve 11. Loops 26 are mounted on the guide rod 17, these loops also receiving the cords 24. From this construction it will be seen that by pulling upon one handle the spout and 70 sprinkler will be moved in one direction, and by pulling upon the other handle the spout and sprinkler will be moved in the opposite direction.

In the form of device shown in Fig. 2 75 the sleeve 11 has an arm 31 forked at its end, the forks being united by a pin 32. A rack bar 33 having teeth 34 extends between the forked ends of the arm, the teeth being ar- 80 ranged to engage the pin 32. This affords means for supporting the spout 15 in its various positions of adjustment, the other construction being as hereinbefore described.

In the construction shown in Fig. 3 of the drawings a clip 36 is formed from sheet 85 metal and is provided with knuckles 37. A supporting strap 38 having knuckles 39 is formed for attachment to the clip 36 as by means of a pin 40. The knuckles and pin are preferably round, and a socket 41 is 90 formed at the end of the strap 38 for the reception of the support 10. This construc- 95 tion is of use in various places and especially where the lip of the tub is located close against the wall and where it would be dif- 100 ficult to place the assembling strap and clip in position. In such instances the clip may be inserted from the end of the tub and slid along the lip to its proper position, and then the straps 38 placed in position and secured by the pin 40.

While I have shown and described herein one form of apparatus embodying my invention, this may be changed to a greater or lesser degree and yet be within the spirit and 105 intent of the invention and I do not therefore limit my invention to the exact construction herein shown and described.

I claim—

1. In a bath tub attachment, clips remov- 110 ably secured to the edge of the tub, loops flexibly secured to said clips, straps secured

to said loops, a supporting bar held by said straps, a sleeve slidable upon said bar, a spout supported by said sleeve, and a connection between said spout and the supply 5 to the tub.

2. In a bath tub attachment, a supporting bar extending lengthwise of the tub, a sleeve slidable longitudinally upon said bar, a holder movably mounted on the sleeve, a 10 spout supported by said holder, and a connection between the spout and the supply to the tub.

3. An attachment for a bath tub including a supporting bar extending lengthwise of 15 the tub, a sleeve slidable longitudinally upon said bar, a holder longitudinally movable upon the sleeve, a spout supported by the holder, and a connection between the spout and the supply to the tub.

20 4. A bath tub attachment including a bar, a sleeve mounted upon the bar, a neck projecting from the sleeve, a holder extending into said neck and movable longitudinally 25 therein, a spout supported by said holder, and a connection between said spout and the supply to the tub.

5. A bath tub attachment including a bar, a sleeve slidably mounted upon the bar, a neck projecting from the sleeve, a holder 30 extending into said neck and movable longitudinally therein, a spout supported by said holder, and a connection between said spout and the supply to the tub.

35 6. An attachment for a bath tub including a supporting bar, a sleeve mounted on the bar, a guide bar, a spout supported by said sleeve and guided along the guide bar, and a connection between said spout and the supply to the tub.

40 7. A bath tub attachment including a sup-

porting bar, a sleeve slidably mounted on the bar, a guide bar, a spout supported by said sleeve and guided by said guide bar and slidably along the latter, and a connection between the spout and the supply to 45 the tub.

8. A bath tub attachment including a bar, means for supporting the bar, a sleeve slidably mounted upon the bar, a spout supported by said sleeve, a guide rod, a guide 50 secured to the spout and in engagement with said rod, and a connection between said spout and the supply to the tub.

9. A bath tub attachment including a bar, a sleeve slidably mounted upon the bar, a 55 spout supported by said sleeve, a guide rod suspended from said bar, a guide secured to the spout and through which said bar extends, and a connection between the spout and the supply to the tub.

60 10. A bath tub attachment including a bar, a sleeve slidably mounted on the bar, a spout supported by the sleeve but having movement independently thereof, a guide rod, a guide secured to the spout and in engagement with the rod, and a connection between said spout and the supply to the tub.

65 11. In a bath tub attachment, clips removably secured to the edge of the tub, loops flexibly secured to said clips, straps secured to said loops, a supporting bar suspended from said straps within the tub, a sleeve freely slidable upon said bar, a spout supported by said sleeve, and a connection between said spout and the supply to the tub.

70 MANO JEFFERSON.
